UNITED STATES PATENT OFFICE

109,155

DESIGN FOR A HAIR WAVING MACHINE

Floyd V. Schleimer, San Francisco, Calif., assignor to Duart Manufacturing Co. Ltd., formerly Pacific Hair Goods Company, San Francisco, Calif., a corporation of California

Application September 21, 1937, Serial No. 71,707

Term of patent 7 years

To all whom it may concern:

Be it known that I, Floyd V. Schleimer, a citizen of the United States and a resident of the city and county of San Francisco, State of California, have invented a new, original, and ornamental Design for Hair Waving Machines, of which the following is a specification, reference being had to the accompanying drawing, forming a part thereof.

Referring to the drawing:

Fig. 1 is a front perspective view of a hair waving machine showing my new design.

Fig. 2 is a rear perspective view thereof.

I claim:

The ornamental design for a hair waving machine, as shown.

FLOYD V. SCHLEIMER.
